WELL BIT

Louis A. Gauthey, Glendale, and William C. Kuykendall, Huntington Park, Calif.; said Kuykendall assignor to said Gauthey

Application July 23, 1937, Serial No. 155,240

11 Claims. (Cl. 255—61)

This invention relates to well drilling tools and relates more particularly to a well bit for use in the rotary method of deep well drilling. A general object of this invention is to provide a rotary well drilling bit that is very rapid in its penetration of the earth formation and that is inexpensive to manufacture and to recondition after use.

The roller well bits now in general use embody pairs or pluralities of broad roller cutters. Such roller bits or rock bits have certain limitations and undesirable characteristics. For example, a roller bit is not successful in sticky or plastic earth formations or in mixed or varied earth formations, due to its tendency to track without cutting and due to its tendency to become balled up due to accumulations of mud and cuttings. Roller bits are also expensive to operate because it is necessary to completely replace the roller cutters, the cutter bearings and the cutter supporting shafts after each run.

Another object of this invention is to provide a rotary well bit that is efficient and very rapid in its cutting operation in hard earth formations and in mixed or varied earth formations.

Another object of this invention is to provide a rotary well drilling bit that embodies a single rotatable cutter and, therefore, is very inexpensive to manufacture and to recondition after use.

Another object of this invention is to provide a rotary well drilling bit that embodies a single toothed rotatable cutter of substantial diameter and of short axial extent or thickness.

Another object of this invention is to provide a rotary well drilling bit of the character mentioned that embodies spaced drag type blades engaging the earth formation to balance the rotatable cutter and to maintain it in proper cooperation with the earth formation, and to bear on the side wall of the well to stabilize the bit.

Another object of this invention is to provide a rotary well drilling bit of the character mentioned in which the rotatable cutter is formed and mounted so that its teeth have a very efficient gouging engagement with the earth formation as distinguished from the crushing action of the teeth of typical roller cutters.

A further object of this invention is to provide a rotary well bit of the character mentioned embodying an improved system of fluid passages and discharge ports for effecting the full flushing of the rotatable cutter and the blades and the agitation of the cuttings in the well bore without in-

juring the cutter or the blades by the erosive action of the discharged fluid under pressure.

The various objects and features of my invention will be fully understood from the following detailed description of a typical preferred form and application of the invention, throughout which description reference is made to the accompanying drawings, in which:

Fig. 1 is a side elevation of the improved bit provided by this invention. Fig. 2 is a bottom view of the bit. Fig. 3 is an enlarged, fragmentary side elevation of the bit illustrating one side or face of the rotatable cutter. Fig. 4 is a horizontal detailed sectional view taken as indicated by line 4—4 on Fig. 3, and Fig. 5 is a reduced diagrammatic view illustrating the manner in which the rotatable cutter and the blades engage the earth formation.

The rotary well bit provided by this invention includes, generally, a shank or body 10 having a depending leg 11, a cutter 12 supported on the leg 11 for rotation about a transverse axis and spaced cutting and stabilizing blades 13 and 14 projecting from the lower end of the body 10.

The shank or body 10 of the bit is intended to be connected with the lower end of a rotary well drilling string. The body 10 may be a simple, integral or one-piece member as illustrated in the drawings. Means is provided at the upper end of the body 10 for connecting it with the well drilling string. In the particular case illustrated a tapered screw-threaded socket 15 is provided in the upper end of the body 10 to facilitate its connection with the string. The shank or body 10 is preferably cylindrical and its lower end is generally horizontal and may be slightly convex. The leg 11 projects downwardly or vertically from the lower end of the body 10 and is preferably integral with the body. In accordance with the invention the leg 11 is offset from the vertical or central axis of the body 10. The leg 11 preferably projects outwardly slightly at the lower end of the body 10 and its inner and outer sides 16 and 17 are substantially vertical. The inner side 16 of the leg 11 is flat and tangent to a circle concentric with the vertical axis of the body 10. The outer side 17 of the leg 11 may be suitably cylindrically rounded and the lower end of the leg may be rounded or convexed.

The cutter 12 is rotatably supported at the inner side 16 of the leg 11 for rotation about a substantially horizontal or transverse axis to act on the earth formation at the bottom of the well

bore and the formation at the side wall of the well bore adjacent the bottom. The cutter 12 has a diameter that is great relative to its thickness or axial length, and, therefore, may be termed a semi-disc cutter. The periphery of the cutter 12 is provided with cutting teeth. It is preferred to provide two rows of circumferentially spaced teeth 18 on the periphery of the cutter 12 and relate the teeth 18 so that the teeth of one row are offset with relation to the teeth of the other row. The cutting teeth 18 are preferably large and deep and the two rows of teeth are separated by a circumferential groove 19. While the teeth 18 may be straight and axial it is preferred to pitch or spiral the teeth as illustrated in the drawings. The crests or active edges 20 of the teeth 18 are curved to conform to the wall of the well bore as will be subsequently described. The end or side 22 of the cutter 12 which opposes the inner side 16 of the leg 11 is preferably flat. The opposite side 23 of the cutter 12 is concaved or dished so that the teeth 18 at the leading side of the cutter may more effectively dig or bite into the earth formation.

The means for rotatably supporting or mounting the cutter 12 on the leg 11 is preferably a simple anti-friction means. The cutter 12 is provided with a central longitudinal opening 24 and a recess 25 in the side 23 around the opening 24. An anti-friction roller bearing 26 is provided in the opening 24 and a pin 27 passes through the bearing 26 and is supported by the leg 11 whereby the bearing 26 rotatably supports the cutter 12 on the pin. The bearing 26 may be of conventional design and construction and the pin 27 is suitably hardened. A head 28 is provided on one end of the pin 27 and is received in the recess 25. The opposite end portion of the pin 27 is received in an opening 30 in the leg 11. Welding 31 may rigidly fix the pin 27 in the opening 30. A hardened thrust washer 32 is provided on the pin 27 to transmit end thrusts from the side 22 of the cutter 12 to the inner side 16 of the leg 11. The thrust washer 32 may be partially recessed in the cutter 12 and the leg 11. The opening 30 receiving the cutter supporting pin 27 is horizontal and is located so that the cutter 12 supported by the pin projects downwardly beyond the lower end of the leg 11 and laterally or transversely beyond the forward edge of the leg 11 relative to the direction of rotation of the well bit.

The location of the rotatable cutter 12 is an important feature of the invention. The axis of rotation of the cutter 12 is substantially horizontal or transverse of the vertical axis of the bit body 10 and is tangent to a circle concentric with said axis. Further, the cutter 12 is offset from or spaced at one side of the vertical axis of the bit body 10 in the direction of the leg 11 so that its side 23 is adjacent but spaced from said axis. As illustrated in Figs. 2 and 4 of the drawings where the arrow X indicates the direction of rotation of the bit the cutter 12 projects forwardly beyond the leading edge of the leg 11 relative to the direction of rotation of the bit, so that the teeth 18 at the leading portion of the cutter 12 cut or gouge into the formation at the side wall of the well bore adjacent the bottom of the bore. The offset cutter 12 also projects downwardly beyond the lower end of the leg 11 and, of course, its teeth 18 act on the bottom of the well bore. As best illustrated in Figs. 3 and 5 of the drawings the rotatable cutter 12 of large diameter located as described above acts on the bottom of the well bore and the side wall of the well bore adja-

cent its bottom to give the wall the dished or concaved configuration shown at Y in Fig. 5. The engagement of the cutter teeth 18 with the earth formation causes the cutter 12 to rotate on its axis in the direction indicated by the arrow Z. The location of the cutter 12, the bodily rotation of the cutter with the bit body 10, the independent rotation of the cutter 12 on its own axis and the shape of the teeth 18 cause the teeth to successively shear and gouge into the earth formation to be particularly effective and rapid in their cutting action. The teeth 18 of the two rows of teeth are spiralled in such a manner that they are particularly effective in cutting through the earth formation and the staggered relation of the teeth gives the cutter 12 a maximum cutting action with a substantial spacing between the adjacent teeth of the rows. The cutter 12 is of substantial diameter relative to the diameter of the well bore.

The blades 13 and 14 are the dragging or scraping cutting parts of the tool and are rigid with the bit body 10. In the preferred construction the blades 13 and 14 are integral with the body 10. The two blades 13 and 14 project downwardly from the lower end of the body and are substantially vertical. The blades 13 and 14 are flat plate-like parts having parallel opposite sides. In accordance with the invention the blades 13 and 14 are located at the opposite side of the axis of rotation of the body 10 from the cutter 12 and are in substantially V-relation, that is, they converge inwardly toward the central axis of the bit to have their inner portions join. The blades 13 and 14 are proportioned to project laterally or horizontally beyond the periphery of the body 10 and their outer edges are adapted to act on the wall of the well bore. The blades 13 and 14 have upper active edges 34 and 35, respectively, that are straight and substantially vertical and lower outer edges 36 and 37, respectively, that are curved downwardly and inwardly relative to the axis of rotation of the tool. The lower ends of the blades 13 and 14 are preferably inclined upwardly and inwardly to more effectively act on the inner portion of the well bore. The active edges of the blades 13 and 14 may be bevelled, although it is preferred to make the straight edge portions 34 and 35 comparatively wide to have extensive bearing cooperation with the side wall of the well.

The parts are related so that the blade 13 acts on the earth formation substantially diametrically opposite the point or line of engagement of the cutter 12 with the formation. Figs. 2 and 4 of the drawings best illustrate this relationship between the blade 13 and the cutter 12. The blade 14 is spaced between the leading portion of the cutter 12 and the blade 13. With the relationship described above the blades 13 and 14 cooperate with the earth formation to maintain the rotatable cutter 12 in cutting cooperation with the earth formation. The lower curved edges 36 and 37 of the blades 13 and 14 have cutting cooperation with the dished wall portion Y of the well bore to assist in cutting away the formation and to scrape away the formation loosened by the teeth 18 of the cutter 12. The upper edge portions 34 and 35 of the blades 13 and 14 bear on the cylindrical side wall of the well bore to dependably stabilize the bit. A relatively large horizontal opening 38 is provided in the connected inner portions of the joined blades 13 and 14 to facilitate the assembly of the pin 27 and to assist in preventing the mud and cuttings from ac-

cumulating on the bit. The opening 38 is sufficiently large in diameter to pass the pin 27 and its head 28 whereby the pin may be inserted through the bearing 26 and into the opening 30.

The invention provides a novel and particularly effective system of ports for flushing the rotatable cutter 12 and the blades 13 and 14. The lower portion of the socket 15 receives the circulation fluid from the drilling string and forms a fluid distributing chamber. A plurality of fluid discharge ports 40 is provided in the body 10 to effect the flushing of the rotatable cutter 12. The ports 40 extend downwardly through the body 10 from the lower end of the socket 15 to the lower end of the body. The ports 40 are preferably aligned or arranged in a row and discharge downwardly at the side 23 of the cutter 12. The ports 40 are transversely elongated to discharge relatively broad streams of fluid across the side 23 of the cutter 12. In the arrangement illustrated there are three aligned ports 40 positioned so that two of the ports discharge downwardly across the face 23 of the upwardly moving trailing portion of the cutter 12. The outermost ports 40 of the row or series of ports are inclined downwardly and outwardly, as best illustrated in Fig. 3 of the drawings. A port 41 is provided in the body 10 and extends downwardly from the lower end of the socket 15 to the lower end of the body to discharge a stream of fluid against the teeth 18 of the cutter 12. The port 41 is elongate in transverse cross section and has its major transverse axis axial relative to the cutter 12 to discharge a broad stream of fluid that impinges against both rows of teeth 18. A port 42 extends downwardly from the lower end of the socket to the lower end of the body and is positioned to discharge a stream of fluid downwardly into the groove 19 between the rows of cutters 18 to flush mud and cuttings from the groove. The port 42 may be round or cylindrical and may discharge substantially directly downwardly into the groove 19.

The means for flushing the blade 13 comprises a fluid discharge port 43. The port 43 extends downwardly and outwardly from the lower end of the socket 15 and passes through a projection or reinforcement 44 on the upper part of the leading face of the blade 13. The port 43 is elongate in transverse cross section and has its major transverse axis substantially parallel with the leading face of the blade 13 to discharge a broad stream of circulation of fluid downwardly across the leading face of the blade. The means for flushing the blade 14 comprises a fluid discharge port 45 extending downwardly through the body 10 from the socket 15 to the lower end of the body. The discharge end of the port 45 is immediately in front of the leading side of the blade 14 relative to the direction of rotation of the bit. The port 45 is preferably elongate in transverse cross section and has its major transverse axis substantially parallel with the leading face of the blade 14 to discharge a broad stream of circulation fluid downwardly and outwardly across the leading face of the blade. The fluid discharged from the ports 43 and 45 effectively clears the blades 13 and 14, respectively, of cuttings and mud.

It is believed that the operation of the bit provided by this invention will be readily understood from the foregoing detailed description. In operation the bit body 10 is connected with the lower end of a rotary well drilling string which is rotated and fed downwardly in the usual manner.

As described above, the teeth 18 of the cutter 12

act on the wall of the well bore at the bottom of the bore and at the side of the bore adjacent the bottom to give the bore the dished or concaved wall Y shown in Fig. 5. The location and shape of the cutter 12 are such that the teeth 18 have a combined scraping and gouging engagement with the formation which is particularly rapid in cutting away the formation. The cutter 12 turns about its own axis at a relatively slow rate so that the teeth 18 successively come into cutting engagement with the earth formation. The spaced radiating blades 13 and 14 engage the wall of the well bore to maintain the cutter 12 in proper engagement with the earth formation and to assist in the cutting action. Further, the broad substantially vertical upper faces 34 and 35 of the blades 13 and 14, respectively, have bearing engagement with the side wall of the bore to stabilize the bit. The lower curved surfaces or edges 36 and 37 of the blades 13 and 14, respectively, are shaped to assist in cutting the earth formation at the dished portion Y of the well.

The circulation fluid is pumped downwardly through the drilling string in the usual manner to discharge from the ports of the body 10. The fluid discharged from the ports 41 and 42 flushes the cutters 12 to prevent mud and cuttings from accumulating on the cutter. The fluid discharged from the ports 40 flushes across the face 23 of the cutter 12 to clear the same. Further, the fluid discharging from the ports 40 or certain of them discharges outwardly through the opening 38 to remove the mud and cuttings from the central portion of the bit and the opening 38 forms an effective outlet for the mud and cuttings. The ports 43 and 45 discharge broad streams of fluid which fully flush the active forward faces of the blades 13 and 14.

Having described only a typical preferred form and application of our invention, we do not wish to be limited or restricted to the specific details herein set forth, but wish to reserve to ourselves any variations or modifications that may appear to those skilled in the art or fall within the scope of the following claims.

Having described our invention, we claim:

1. A bit for use on a rotary well drilling string comprising a body to be connected with the string to be rotated thereby, a disc-like cutter having spaced rows of circumferentially spaced teeth on its periphery, the teeth of one row being offset from the teeth of the adjacent row, means supporting the cutter at the lower end of the body to rotate about a substantially horizontal axis where it projects downwardly and laterally at one side of the body, blades projecting downwardly and laterally from the body at the other side of the body, and separate means for flushing the cutter and blades.

2. A bit for use on a rotary well drilling string comprising a body to be connected with the string to be rotated thereby, a disc-like cutter having spaced rows of circumferentially spaced teeth on its periphery, the teeth of one row being offset from the teeth of the adjacent row, means supporting the cutter at the lower end of the body to rotate about a substantially horizontal axis where it projects downwardly and laterally at one side of the body, said means including a leg depending from the lower end of the body at one side of the vertical axis of the body, the leg having a substantially horizontal opening, and a pin secured in the opening projecting from the inner side of the leg and rotatably supporting the cut-

- ter, and a pair of outwardly radiating blades projecting downwardly and laterally at the other side of the body, the blades having an opening aligned with the first mentioned opening and 5 adapted to pass the pin.
3. A bit for use on a rotary well drilling string comprising a body to be connected with the string to be rotated thereby, a disc-like cutter having spaced rows of circumferentially spaced teeth on 10 its periphery, the teeth of one row being offset from the teeth of the adjacent row, means supporting the cutter at the lower end of the body to rotate about a substantially horizontal axis where it projects downwardly and laterally at one side 15 of the body, blades projecting downwardly and laterally from the body at the other side of the body, and separate means for flushing the cutter and blades, the last named means comprising a row of ports in the body discharging downward- 20 ly across the forward face of the cutter, a port in the body discharging downwardly between the rows of teeth and a port in the body discharging downwardly across the forward face of each blade.
- 25 4. A rotary well drilling bit comprising a body to be rotated in the well, a rotatable cutter, means supporting the cutter at the lower end of the body for rotation about an axis substantially transverse of the axis of rotation of the body and tangent to a circle concentric with the axis of 30 rotation of the body to have the cutter project downwardly and laterally beyond the lower end of the body so that the cutter acts on the bottom wall of the well and the side wall of the well, and a blade rigid with the body projecting downwardly and laterally beyond the lower end of the body to engage the bottom wall of the well and 35 to engage the side wall of the well at a point substantially opposite the point of engagement of the said cutter with the side wall to maintain the cutter in active engagement with the side wall of the well.
- 40 5. A rotary well drilling bit comprising a body to be rotated in the well, a rotatable cutter, means supporting the cutter at the lower end 45 of the body for rotation about an axis substantially transverse of the axis of rotation of the body and tangent to a circle concentric with the axis of rotation of the body so that the cutter projects downwardly and laterally beyond the lower end of the body to act on the bottom wall of the well and to act on the side wall of the well at one side of the bit, and two laterally diverging cutting blades rigid with the body and 50 projecting downwardly and laterally beyond the lower end of the body to act on the bottom and side walls of the well and maintain the cutter in active engagement with the well wall, one blade being positioned to act on the side wall of the well at a point substantially opposite the point of engagement of the cutter with the side wall of the well.
- 55 6. A bit for use on a rotary well drilling string comprising a body to be connected with the string to be rotated thereby, a disc-like cutter, means supporting the cutter at the lower end 60 of the body for rotation about an axis substantially transverse of and laterally offset from the axis of rotation of the body so that the cutter projects downwardly beyond the lower end of the body and laterally beyond one side of the body, and laterally diverging drag type blades rigidly secured to the body and projecting beyond its lower end and projecting laterally beyond 65 the other side of the body.
- 70 7. A bit for use on a rotary well drilling string comprising a body to be connected with the string to be rotated thereby, a depending leg on the lower end of the body, a substantially disc-shaped cutter having peripheral cutting teeth, means supporting the cutter on the body leg for rotation about a substantially horizontal axis offset from the central vertical axis of the body so that the cutter projects downwardly and laterally from one side of the body to have its teeth act 75 on the earth formation to provide the bottom of the well with a concaved outer portion, and a cutting blade rigid with the body and projecting downwardly and laterally from the lower end of the body at the other side of the body, the blade being shaped to conform to said bottom portion of the well and to bear on the side wall of the well.
8. A bit for use on a rotary well drilling string comprising a body to be connected with the string to be rotated thereby, a substantially disc-shaped cutter having peripheral cutting teeth, means supporting the cutter on the body for rotation about a substantially horizontal axis where it projects downwardly and laterally from one side of the body so that its teeth act on the side wall and the bottom wall of the well to make the outer portion of the well bottom concave, and two laterally diverging cutting blades projecting downwardly and laterally from the body, the 25 blades having active edges curved to conform to the concave portion of the well wall, one blade being positioned to act on the side wall of the well at a point substantially opposite the point of engagement of the cutter with the side wall, the other blade being spaced between the cutter and the first mentioned blade.
- 30 9. A bit for use on a rotary well drilling string comprising a body to be connected with the string to be rotated thereby, a substantially disc-shaped cutter having peripheral cutting teeth, means supporting the cutter on the body for rotation about a substantially horizontal axis offset from the vertical axis of the body where it projects downwardly and laterally from one side of the body so that its teeth act on the side wall and the bottom wall of the well to make the outer portion of the well bottom concave, and blades rigid with the body projecting downwardly and outwardly from the other side of the body, the blades having broad upper edges bearing on the side wall of the well and lower active edges curved to conform to the concave portion of the well wall.
- 35 10. A rotary well drilling bit comprising a body to be rotated in the well, a rotatable cutter, means supporting the cutter at the lower end of the body for rotation about an axis substantially transverse of the axis of rotation of the body so that the cutter projects laterally beyond the body to act on the earth formation at the bottom and at one side of the well bore, a cutting blade rigid with the body projecting downwardly and laterally from the body and acting on the formation at the bottom and the other side of the well bore, and a cutting blade rigid with the body spaced between the leading part of the cutter and the trailing side of the first named blade relative to the direction of rotation of the body and projecting downwardly and outwardly from the body to act on the bottom and side wall of the well.
- 40 11. A rotary well drilling bit comprising a body, a single cutter mounted on the lower end of the body at one side of its vertical axis to rotate 45

about a substantially horizontal axis and to project downwardly and outwardly from the body to make a dished annular cut in the bottom of the well, and laterally diverging cutting blades 5 rigid with the body and projecting downwardly and laterally from the lower end of the body at

the other side of its vertical axis to assist the rotatable cutter in making said cut and to maintain the cutter in position to cut the bore to gauge.

LOUIS A. GAUTHHEY.

WILLIAM C. KUYKENDALL.
